UNITED STATES PATENT OFFICE.

ALVAH C. SPENCER, OF BEVERLY, MASSACHUSETTS, ASSIGNOR TO UNITED SHOE MACHINERY COMPANY, OF PATERSON, NEW JERSEY, A CORPORATION OF NEW JERSEY.

IMPRESSION OR Imitation-STITCH MACHINE.

No. 917,807.

Specification of Letters Patent. Patented April 13, 1909.

Application filed May 10, 1907. Serial No. 372,856.

To all whom it may concern:

Be it known that I, ALVAH C. SPENCER, citizen of the United States, residing at Beverly, in the county of Essex and State 5 of Massachusetts, have invented certain new and useful Improvements in Impression or Imitation-Stitch Machines; and I do hereby declare the following to be a full, clear, and exact description of the invention, such as 10 will enable others skilled in the art to which it appertains to make and use the same.

The present invention relates to impression or imitation stitch machines which are used in the manufacture of boots and shoes 15 to produce ornamental impressions upon the upper surface of the projecting edge of the sole and which usually comprise an indenting tool provided with teeth shaped and spaced to produce the desired form of indentations 20 and a work support for engaging the sole of a shoe and supporting it against the thrust of the indenting tool.

The object of the invention is to provide a machine of this class in which the marginal 25 portion of the sole upon which the machine operates is uniformly supported by the work support against the thrust of the indenting tool in such manner that the indentations may be accurately and uniformly produced 30 without danger of distorting or bending the marginal portion of the sole away from the upper and thus injuring the appearance of the boot or shoe.

In accordance with the principal feature of 35 the invention the marginal portion of the sole is uniformly supported and its upper surface properly presented to the indenting tool by a work support so mounted and arranged that it automatically adapts itself 40 to that portion of the sole with which it has engagement. With the work support thus mounted and arranged the upper surface of the work support automatically shifts to accommodate any variation in the curvature 45 or shape of the under surface of the sole so that the support always presents a bearing surface for the sole properly positioned to effectively sustain and resist the thrust exerted upon the sole by the indenting tool 50 and to support the sole in such relation to the indenting tool that there is no tendency for the indenting tool to bend the marginal portion of the sole away from the upper and thus distort the sole so as to injure the 55 appearance of the boot or shoe. A machine

embodiment this form of work support may therefore be successfully employed upon shoes in which the sole of the shoe is not of uniform convexity throughout the length of that portion upon which the indentations 60 are made and under conditions where the employment of work supports such as have heretofore been embodied in this class of machines would result in a bending or distortion of the marginal portion of the sole or the 65 production of otherwise imperfect work.

The specific manner in which the work support is mounted and arranged so that it may automatically conform to the surface of the sole with which it is in engagement is 70 not essential and may be varied as found desirable or expedient. It is desirable however, to so mount the work support that it is directly supported in line with the thrust exerted upon the upper surface of the sole by 75 the indenting tool and this manner of supporting the work support forms an additional feature of the invention.

Broadly considered the invention contemplates actuating the indenting tool in any 80 suitable manner to produce the indentations. In the preferred form of the invention however, the movements which are imparted to the tool are substantially perpendicular to the surface of the stock and are produced by 85 hammer mechanism which causes the tool to strike a series of blows in rapid succession upon the work.

The invention also contemplates the use of 90 any suitable form of indenting tool but on account of the simplicity of construction and the speed at which such a machine can be operated, a tool is preferably used which is in the form of a wheel provided with teeth shaped and spaced to produce the desired form of 95 indentation and arranged to rotate to bring successive teeth into engagement with the work. This wheel may be of the form which has heretofore been used in impression or imitation stitch machines and like such 100 wheels is preferably frusto-conical in shape with its base or larger diameter directed toward the shoe upper in order that the indentations which are formed upon the shoe sole 105 may project beneath the outwardly bulging portion of the upper.

The features of the invention will be clearly understood from an inspection of the accompanying drawings, in which—

Figure 1 is a view in side elevation and 110

23
partly in section of the upper portion of an impression or imitation stitch machine embodying said features in their preferred form. Fig. 2 is a side elevation of the work support and its carrier block detached from the arm on which the work support is mounted; and Fig. 3 is an elevation looking toward the left in Fig. 2.

Referring to the drawings the indenting tool 10 consists of a frusto-conical wheel 1 provided with teeth upon its periphery suitably formed and shaped to produce the desired indentations. This wheel is mounted to rotate freely on a stud 2 secured by means of a 15 split clamp in the lower end of a tool-carrier 3. The indenting wheel is arranged to act upon the projecting edge of a shoe sole as indicated in Fig. 1 and has its base or larger diameter directed outwardly so that the portion 20 of the wheel which contacts with the sole extends beneath the bulging portion of the shoe upper. The tool carrier 3 is mounted to slide vertically in a guideway formed in the front portion of the overhanging head of 25 the machine and when no work is in the machine assumes its lowest position under the force of gravity. When the work is placed in the machine the tool carrier is raised so as to bring its upper end into a position to 30 be acted upon by a rotating hammer mechanism. This hammer mechanism comprises a carrier 4 secured upon the forward end of a driving shaft 5 and having mounted therein a series of cylindrical rolls 6 which during the 35 rotation of the shaft and carrier act successively upon the upper end of the tool carrier. Upon the rear end of the driving shaft 5 are secured fast and loose pulleys 7 and 8 by means of which a rapid rotation is imparted 40 to the driving shaft. A belt shifter 9 serves as a convenient means for shifting the belt from one pulley to the other to throw the driving shaft into and out of operation.

The shoe is supported against the thrust of 45 the indenting tool by means of a work support 10 which as shown in the drawings is in the form of a small circular plate. The work supporting plate 10 is formed on the upper end of a block 11 supported in the bifurcated 50 end of a carrier 12 by a pivot 13. The pivot 13 is arranged with its axis substantially in line with the feed of the sole between the work support and wheel and the work support is therefore free to shift as the shoe is 55 fed to accommodate any variation in the lateral curvature of the under surface of the sole and thus automatically adapt itself to that portion of the sole with which it is in engagement and maintain its surface in 60 proper relation with the indenting wheel. The pivot pin is also arranged directly under the indenting wheel 1 where it is in direct line with the thrust exerted upon the sole by the indenting wheel. The pivot pin therefore 65 provides one form of means for supporting

the work support so that it may automatically adapt itself to the surface with which it is in engagement and by which the work support is directly supported in line with the thrust exerted upon the sole by the indenting 70 tool.

The front end of the wheel is inclosed by an upper guard consisting of a plate 21, extending across two arms, which are pivotally mounted upon the frame of the machine so that the indenting tool can move vertically 75 without exerting a rubbing action upon the shoe upper which is held out of engagement therewith by means of the plate 21.

The work support carrier 12 is mounted 80 upon a pivot pin 14 in the end of an arm 15 and is provided with a nose 16 resting upon a bearing surface 17 on the arm. The arm 15 may be supported and operated in introducing and removing the work in the usual 85 manner.

The nature and scope of the present invention having been indicated and a machine embodying the various features of the invention in their preferred form having been specifically described, what is claimed is:—

1. An impression or imitation stitch machine having in combination an indenting tool arranged to act upon the upper surface of the projecting edge of the shoe, a work 95 support arranged to engage the tread surface of the sole and means for supporting the work support against the thrust of the tool while permitting it to move under the force exerted by the tool on the work to automatically adapt itself to that portion of the sole with which it is in engagement. 100

2. An impression or imitation stitch machine having in combination an indenting tool arranged to act upon the upper surface 105 of the projecting edge of the sole, means for causing the tool to strike a series of blows in rapid succession upon the work, a work support arranged to engage the tread surface of the sole of a shoe and means for supporting 110 the work support against the thrust of the tool while permitting it to move under the force exerted by the tool on the work to automatically adapt itself to that portion of the sole with which it is in engagement. 115

3. An impression or imitation stitch machine having in combination an indenting wheel arranged to act upon the upper surface of the projecting edge of the sole, means for causing the wheel to strike a series of blows 120 in rapid succession upon the work, a work support arranged to engage the tread surface of the sole and means for supporting the work support against the thrust of the wheel while permitting it to move under the force 125 exerted by the wheel on the work to automatically adapt itself to the portion of the sole with which it is in engagement.

4. An impression or imitation stitch machine having in combination an indenting 130

tool arranged to act upon the upper surface of the projecting edge of the sole, a work support arranged to engage the tread surface of the sole, and a support for the work support in the line of the thrust exerted upon the sole by the indenting tool arranged to permit the work support to move under the force exerted by the tool on the work to automatically adapt itself to the portion of the sole with which it is in engagement.

5. An impression or imitation stitch machine having in combination an indenting tool arranged to act upon the upper surface of the projecting edge of the sole, and a work support arranged to engage the tread surface of the sole and mounted for free movement under the force exerted by the tool on the work about an axis in line with the feed of the work to automatically adapt itself to the 15 portion of the sole with which it is in engagement.

20. 6. An impression or imitation stitch ma-

chine having in combination an indenting wheel arranged to engage the upper surface of the projecting edge of the sole of a shoe, a work support arranged to engage the tread surface of the sole, a pivotal support for the work support arranged in line with the thrust exerted upon the sole by the indenting wheel and having its axis arranged in the direction of the feed of the sole between the indenting wheel and work support said pivotal support permitting the work support to move under the force exerted on the work by the wheel to automatically adapt itself to the portion of the sole with which it is in engagement.

25. 30. 35. In testimony whereof I affix my signature, in presence of two witnesses.

ALVAH C. SPENCER.
